UNITED STATES PATENT OFFICE.

PAUL R. LA BRANT AND ADOLPH C. NORDHAUGEN, OF STANLEY, NORTH DAKOTA.

AUTOMOBILE-WHEEL-RIM-Straightening Device.

1,400,297.

Specification of Letters Patent. Patented Dec. 13, 1921.

Application filed February 2, 1921. Serial No. 441,394.

To all whom it may concern:

Be it known that we, PAUL R. LA BRANT and ADOLPH C. NORDHAUGEN, citizens of the United States, residing at Stanley, in the county of Mountrail and State of North Dakota, have invented certain new and useful Improvements in Automobile-Wheel-Rim-Straightening Devices, of which the following is a specification, reference being had to the accompanying drawings.

This invention relates to improvements in rim straighteners and has for particular object thereof the provision of a device for straightening the rims of automobile wheels which are utilized for holding tires of the clincher type.

An important object of the invention is to provide a device of this character which at one operation will restore a bent rim to its proper shaping.

A further object of the invention is to provide a device of this character comprising a tool embodying a pair of peculiarly shaped jaws adapted when forced together to form therebetween a rim, together with means for forcing the jaws into engagement.

Other objects and advantages of our invention will become apparent throughout the course of the following description.

In the accompanying drawings, wherein for the purpose of illustration we have shown preferred embodiments of our invention whereby the above objects are attained:

Figure 1 is a side elevation partly in section showing our tool applied to straightening a rim, the dotted lines indicating the position of the tool and rim flange at the time of initial engagement.

Fig. 2 is a section on the line 2—2 of Fig. 5.

Fig. 3 is a section on the line 2—2 of Fig. 5 and looking in the opposite direction from the arrows,

Fig. 4 is a fragmentary plan view illustrating one form of operating mechanism, and

Fig. 5 is a side elevation illustrating a slightly modified form thereof.

Referring now more particularly to the drawings, the numeral 10 indicates a shank having secured thereto and formed integrally therewith, a head or jaw member 11.

This jaw member is transversely grooved as at 12 adjacent one edge thereof to form

at the edge a tongue 13 which is arcuately curved to conform to the curvature of the rim with which the tool is to be employed. This tongue conforms to the proper curvature of the undercut or bead-receiving portion of the rim flange 14. The opposite face 15 of the groove 12 from the tongue 13 inclines toward the base of the groove and toward the base of the tongue 13 for purpose presently to appear. Slidably mounted upon the shank 10 is a second jaw 16 provided in the face thereof next adjacent the jaw 11 with an arcuate groove 17 corresponding to the proper curvature of and adapted to receive the outer face of the bend of the flange of the rim.

It will be seen that when the jaws are placed in position upon a flange which is bent with the inner edge of the flange engaging in the groove 12 and the outer curve thereof engaged by the groove 17, the deformation of the rim will cause the rim to engage either against the inclined inner face 13^a of the tongue or the inclined wall 15 of the groove which is opposed to this face. If pressure is now applied to the jaw 16 to cause the same to move toward the jaw 11, the inner edge of the flange will be forced to move down the inclined wall with which it is engaged until it arrives at its proper position in the base of the groove.

Any suitable means may be provided for shifting the jaw 16 longitudinally upon the shank 10 which will give sufficient pressure to overcome the resistance afforded by the rim, it being of course understood that this resistance will vary in different types of rims. In the present instance we have illustrated two forms of operating mechanism whereby the shifting of the jaw 16 may be obtained. In Fig. 4, a pivot pin 19 is mounted in the shank 10 and forms a pivot for an eccentric disk 20 having integrally formed therewith an operating handle 20^a by means of which the disk may be rotated about the pivot 19. The shank 10 is likewise continued to form a handle 21 and it will be obvious that by relatively shifting these handles the jaw 16 may be forced toward the jaw 11 as desired. In the form shown in Fig. 5, a longitudinally threaded bearing 22 is formed upon the shank 10 and has mounted therein an externally screw-threaded shaft 23, the inner end of which abuts the under face of the jaw 16 as at 24, the outer end of this shaft is provided with a

handle 25 by means of which the shaft may be rotated to shift the jaw 16 as desired.

It will be obvious that the operating means above disclosed may be greatly varied 5 and it will likewise be obvious that many other changes of a similar character may be resorted to without in any manner departing from the spirit of our invention, and we accordingly do not limit ourselves to the 10 specific structure hereinbefore set forth except as hereinafter claimed.

What we claim is:

In a portable tool for straightening the flanges of rims of automobile wheels, a 15 shank, a stationary jaw carried by the shank and having a groove formed therein and provided at one edge of the jaw with a tongue corresponding to the proper shaping of the bead-receiving under surface of the 20 flange, said tongue and groove being longi-

tudinally arcuately curved to conform to the curvature of the rim, the wall of the groove opposing said tongue being inclined toward the base of said tongue, a shiftable jaw slidably mounted upon the base of said shank and grooved to engage the outer face of the flange to force the flange into the groove on the stationary jaw and into engagement with said tongue to be formed by the latter, and means for shifting said last named jaw to force the flange of the rim into the groove, said tool being adapted to straighten circumferential bends and lateral distortions simultaneously with one operation. 25 30 35

In testimony whereof we hereunto affix our signatures.

PAUL R. LA BRANT.
ADOLPH C. NORDHAUGEN.
